CLAIM

The ornamental design for a pair of spaced-apart exercise handles, as shown and described.

DESCRIPTION

FIG. 1 is a bottom-front perspective view of an embodiment of a pair of spaced-apart exercise handles showing our new design;

FIG. 2 is a rear-bottom perspective view of the embodiment shown in FIG. 1;

FIG. 3 is a front elevational view of the embodiment shown in FIG. 1;

FIG. 4 is a rear elevational view of the embodiment shown in FIG. 1;

FIG. 5 is a bottom plan view of the embodiment shown in FIG. 1;

FIG. 6 is a top plan view of the embodiment shown in FIG. 1;

FIG. 7 is a right side elevational view of the embodiment shown in FIG. 1; and,

FIG. 8 is a left side elevational view of the embodiment shown in FIG. 1.

The broken line portions of the drawing figures are included to show unclaimed subject matter only and form no part of the claimed design. In particular, the connector bar between the exercise handles shown in broken lines forms no part of the claimed invention.
